TRANSFER TRUCK

Robert W. Ledgerwood, Portland, Oreg., assignor to Roll-Away Truck Manufacturing Company, Inc., Portland, Oreg., a corporation of Oregon

Application October 28, 1957, Serial No. 692,745

8 Claims. (Cl. 182—118)

This invention relates to stock transfer trucks or carts, and more particularly to trucks or carts having a ladder carried at one end thereof which includes a mechanism for securing the ladder to the cart in a lowered position.

Generally it is an object of this invention to provide for a transfer truck or cart a ladder and novel mechanism for securing the ladder to the body of the cart whereby, when the ladder is secured, the base of the ladder exerts a predetermined amount of downward thrust against a floor supporting the cart.

Stock transfer trucks are used frequently in storerooms, warehouses and the like in transporting articles from one location to another. It is conventional to equip stock transfer trucks with built-in ladder devices so that the trucks may be used for loading or unloading articles elevated a considerable distance from the floor. The carts are usually of relatively light construction, and often are comprised of aluminum or other material of light mass, to reduce as much as possible the work required to move the cart from one point to another. Conventionally, a ladder incorporated with a truck of this description is movable between raised and lowered positions, to enable the base of the ladder to rest firmly on the ground during use, and to accommodate movement of the truck when the truck is used for transport.

This invention contemplates a hand truck construction wherein the ladder for the truck is mounted at one end of the truck for movement between raised and lowered positions and which includes mechanism for securing the ladder in a lowered position with the ladder exerting a downward thrust on the floor. A bias or spring means included between the body of the cart and the ladder urges the ladder upwardly to a riding position off the floor. This enables the truck to be made ready for transport without having to lift the ladder and hook it into position. Included in the cart is another biasing means, which, when energized, creates a force opposing the force of the spring means which is urging the ladder to its riding position. This other biasing means is energized when the ladder is secured in a lowered position. In its energized state, the force of the other biasing means is greater than the force of the spring means raising the ladder, so that the ladder is urged downwardly against the floor upon energizing of this other biasing means.

By using a pair of biasing means or springs operating in opposition to each other, a number of advantages accrue. For one thing, the ladder is easily shifted to its riding position which contributes to its utility. Most important, the ladder when shifted to a lowered position operates as a brake. Further, a firm grip is established between the ladder and a floor under the ladder which is maintained regardless of any bending occurring in the cart upon loading, which with conventional constructions tends to move the ladder off the floor. This follows from the fact that the ladder is not immovably fixed in position, but instead is secured using a yielding connection. The maintained grip which is produced between the ladder and the floor, regardless of bending or buck-

2

ling in the cart, is particularly advantageous when one considers the light construction which usually characterizes these trucks.

The latch mechanism of this invention includes a foot operated latch member slidably mounted in one of the steps of the ladder for the cart. The mechanism is easily engaged by pressing downwardly with one's foot. The spring for urging the ladder downwardly is interposed between the latch member and the ladder step, and is energized by movement of the latch member into a latching engagement with a catch mounted on the body of the truck. The latch member is easily disconnectable to permit springs associated with the ladder to raise the ladder from the floor readying the truck for transport.

Other objects, features, and advantages are attained by this invention, the invention being described hereinbelow in conjunction with the accompanying drawings wherein:

Fig. 1 is a side view of a transfer truck according to an embodiment of this invention, the truck including a body portion and a ladder slidably mounted for movement up and down at one end thereof;

Fig. 2 is an end view illustrating details of the ladder and latching mechanism of this invention;

Fig. 3 is a section view along the line 3—3 of Fig. 2, slightly enlarged, and showing the base of the ladder and the latch mechanism associated therewith, the latch mechanism being illustrated in a disengaged or unlatched condition; and

Fig. 4 is a view similar to Fig. 3 showing the latch mechanism in an engaged condition.

Referring now to the drawings for a more detailed description of this invention, and more particularly to Figs. 1 and 2, a transfer truck or cart of this invention comprises in general a body portion 10 having a ladder portion indicated at 11 slidably mounted for reciprocation up and down at one end of body 10. Body 10 is comprised of four upstanding frame or chassis members 16 defining the peripheral outline of the body. Extending between and affixed to members 16 are three horizontally disposed shelves 17, 18, and 19. The shelves preferably have a flat or planar upper surface, indicated for shelf 19 at 20, to enable articles to be slid onto and off the shelves when loading and unloading the cart without first lifting the articles.

45 Wheel supports are included for the truck. Affixed to the truck beneath bottom shelf 17 are four wheel mounts indicated at 21 and 22. In the embodiment illustrated, the wheels 22 underneath the rear portion of the truck adjacent ladder 11 are swivel wheels, whereas wheels 21 for the front of the truck are carried in mounts rigidly secured to the front of the truck.

Ladder 11 is comprised of a pair of ladder uprights 26 and 27. Each of the ladder uprights is curved at its upper end to form a loop 28. Loop 28 at the upper end of the ladder provide a handle for gripping onto when climbing the ladder, and also provide support for an occupant's legs when mounted on the upper reaches of the ladder. The ladder uprights are slidably mounted in brackets 31 and 32.

60 Extending between the ladder uprights are three step elements or members 33, 34, and 35. These steps are secured in place at their opposite ends to the ladder uprights, as by connecting sleeve portions 36 encircling the ladder uprights.

65 Interposed between the connecting sleeves 36 for lower step 33, and brackets 32, are a pair of compression springs 37, one for each of the uprights 26, 27. The lower end of each spring seats on a bracket 32, and the upper end of each spring abuts the underside of a sleeve portion 23. Springs 37 function as a biasing means urging the ladder upwardly relative to the body of the cart, so

that the lower ends of the ladder uprights clear a floor supporting the cart. The springs yield under the weight of an occupant to accommodate movement of the ladder downwardly against the floor.

The base of each ladder upright is equipped with a rubber grip, such as grip 38. The grips increase the frictional contact between the ladder uprights and the floor when the ladder is in a lowered position.

Intermediate the ends of lower step 33 and slidably mounted in the step is a foot actuated lever or latch member 41. The latch member is mounted for movement up and down in a suitable aperture formed in the step. The latch member is loosely fitted in the step, so that the latch member can swing slightly from a vertical position.

A transverse angle iron strip 42 is secured to the lower side of step member 33. The downwardly extending flange of this angle iron strip is suitably secured to one of the flanges of an angle iron segment 43. The other flange of strip segment 43 extends horizontally beneath step 33. Latch member 41 extends downwardly through step 33 and thence through a slot 44 provided in the horizontal flange of segment 43.

Referring to Figs. 3 and 4, in the embodiment illustrated, latch member 41 is comprised of an elongated stud portion 46 secured at its upper end to head portion 47. The head portion includes a pedal surface 48. Stud 46 has a notch 49 formed therein on the inner side of the stud portion.

A catch 51 is fastened as by nut and bolt assemblies 52 to the body of the truck. The catch is held intermediate the ends of the lower shelf adjacent ladder 11 and in the path of the latch member when the latch member is moved downwardly. Notch 49 fits over the lip of the catch to engage the catch as shown in Fig. 4.

Encircling stud portion 46 of latch member 41 is a bias means or spring 56 and a washer 45. Spring 56 is a compression spring and exerts, when compressed, a force which exceeds the force created by compressing together springs 37. When latch member 41 is disconnected, washer 45 abuts the horizontal flange of strip 42, and spring 56 extends between the washer and the horizontal flange of segment 43 as in Fig. 3. The spring is energized by movement of the latch member downwardly from the position of Fig. 3 to the position of Fig. 4 which compresses the spring. When compressed, washer 45 seats on the shoulder defined by head portion 47 where it joins stud portion 46.

The latch member and catch constitute mechanism or means for holding the ladder in a lowered position. Spring or bias means 56 operatively interposed between step 33 and the latch member is energized when the latch member and catch are connected.

Latch member 41 is urged downwardly into latching engagement with the catch by pressing downwardly on pedal surface 48. This moves the lower end of the latch member over the catch, the lower end riding over the lip of the catch. The parts lock when notch 49 engages the latch, as in Fig. 4. Release of the latch member is accomplished by pushing downwardly and slightly inwardly on pedal surface 48, which moves notch 49 outwardly and away from the lip of the catch.

It will be noted that this construction has a number of advantages. The ladder, when not in use, is urged upwardly away from the floor by springs 37, which eliminates the need for an operator to lift the ladder manually into a riding position. In a lowered position, the ladder is not immovably fixed in position, but instead is urged downwardly relative to the body of the truck with a predetermined amount of force. Should the outer ends of the cart move upwardly by reason of bending of the cart downwardly intermediate wheels 21, 22 under a heavy load, the ladder still is maintained in engagement with the floor.

The shelves are planar or flat so that a load may be

slid on and off the shelves without having to lift the same. In a lowered position, the ladder acts as a brake preventing the truck from rolling on wheels 21, 22. This facilitates sliding articles onto and off the shelves of the truck. Further, it enables, if desired, an operator to use the top shelf of the cart as an additional step, without danger of the cart shifting beneath the operator.

It is claimed and desired to secure by Letters Patent:

1. A cart comprising a body portion, a ladder portion mounted on said body portion at one end thereof for movement up and down relative to said body portion, and means for detachably holding said ladder portion anchored in a lowered position, said means including a latch member carried by one of said portions connectable with the other of said portions, and bias means carried by one of said portions energized upon connection of said latch member and operable when energized to urge said ladder portion downwardly relative to said body portion.
2. In combination, a cart body portion, a ladder portion slidably mounted at one end thereof for movement up and down relative thereto, wheel support for said body portion, and means for detachably holding said ladder portion anchored in a lowered position, said means including a latch member mounted on one of said portions, a catch mounted on the other of said portions for detachably engaging said latch member, and bias means interposed between said latch member and said one of said portions energized when said catch engages said latch member and operable when energized to urge said ladder portion downwardly relative to said body portion.

3. A cart comprising a body portion, a ladder portion slidably mounted at one end thereof for movement up and down relative thereto, bias means interposed between said body and ladder portions urging said ladder portion upwardly relative to said body portion, a latch member mounted on one of said portions, a catch mounted on the other of said portions for detachably engaging said latch member, and bias means interposed between said latch member and said one of said portions energized when said catch engages said latch member and operable when energized to urge said ladder portion downwardly relative to said body portion.

4. In a hand truck, the combination of a wheel supported body, a ladder slidably mounted for reciprocation relative thereto at one end thereof, bias means interposed between said body and ladder urging said ladder upwardly relative to said body, a catch carried by said body adjacent said ladder, foot operated latch member mounted on said ladder having an end portion detachably engageable with said catch, and bias means interposed between said latch member and ladder energized when said latch member engages said catch and operable when energized to urge said ladder downwardly relative to said body.

5. A cart comprising a wheel supported body, a ladder comprised of a pair of uprights and horizontal steps extending between said uprights slidably mounted at one end of said body for movement up and down relative thereto, a compression spring interposed between said body and at least one of said uprights urging said ladder upwardly relative to said body, a catch carried by said body adjacent said ladder, a foot operated latch member mounted in one of said steps having an end portion detachably engageable with said catch, and a compression spring interposed between said latch member and said one step energized when said latch member engages said catch and operable when energized to urge said ladder downwardly relative to said body.

6. In a hand truck, the combination of a truck body portion, wheel support for said body portion, said body portion including at least one substantially horizontal planar shelf, a ladder portion carried by said body portion at one end thereof for movement up and down relative thereto, and detachable latch means interposed between said ladder and body portions operable to anchor

said ladder portion against a floor supporting the truck thereby to brake the truck, said last mentioned means including a latch member carried by one of said portions connectable with the other of said portions, and bias means carried by one of said portions energized upon connection of said latch member and operable when energized to urge said ladder portion downwardly relative to said body portion.

7. In a hand truck, the combination of a truck portion, wheel support for said body portion, said body portion including at least one substantially horizontal planar shelf, a ladder portion carried by said body portion at one end thereof for movement up and down relative thereto, and detachable latch means interposed between said ladder and body portions operable to anchor said ladder portion against a floor supporting the truck thereby to brake the truck, said last mentioned means having a foot operated latch member mounted on said ladder portion, a catch carried by said body portion adjacent said latch member and engagable with said latch member, and bias means interposed between said latch member and ladder portion energized upon engagement of said latch member with said catch and operable when energized to urge said ladder portion downwardly relative to said body portion.

8. In a hand truck, the combination of a truck body portion, wheel support for said body portion, said body portion including at least one substantially horizontal planar shelf, a ladder portion carried by said body portion at one end thereof for movement up and down relative thereto, bias means interposed between said body and ladder portions urging said ladder portion upwardly relative to said body portion, and detachable latch means interposed between said ladder and body portions operable to anchor said ladder portion against a floor supporting the truck thereby to brake the truck, said latch means including a spring energized when said ladder and body portions are connected by said latch means and operable when energized to urge said ladder portion downwardly against the bias of said bias means.
